UNITED STATES PATENT OFFICE

156,902

AIR CONDITIONER CABINET OR THE LIKE

Joseph M. Lewis, Wichita Falls, Tex.

Application December 30, 1948, Serial No. 150,448

Term of patent 14 years

(Cl. D62—4)

To all whom it may concern:

Be it known that I, Joseph M. Lewis, a citizen of the United States of America, residing at Wichita Falls, in the county of Wichita and State of Texas, have invented a new, original, and ornamental Design for an Air Conditioner Cabinet or the like, of which the following is a specification, reference being had to the accompanying drawing, forming a part thereof.

In the accompanying drawing:

Fig. 1 is a perspective view of an air conditioner cabinet embodying my new design, illustrating the top, front, and side thereof; and

Fig. 2 is a perspective view illustrating the top, rear, and opposite side thereof.

I claim:

The ornamental design for an air conditioner cabinet or the like, substantially as shown.

JOSEPH M. LEWIS.
